SILENCER

Hiram Hamilton Maxim, Hartford, Conn., assignor to The Maxim Silencer Company, Hartford, Conn., a corporation of Connecticut

Application December 9, 1936, Serial No. 114,989

17 Claims. (CL 181—48)

The present invention relates to silencers for internal combustion engines. More particularly it represents a specialized application of acoustic principles, well known in the art, to the design of silencers adapted for use on submarine vessels.

5 Silencers for submarines are generally located in the super-structure of the vessel and must be flooded with sea water when the vessel is submerged to avoid any interference with the trim due to air pockets. The flooding and draining of the silencer must be accomplished very quickly. The silencer must be so constructed that the entire interior is readily accessible for 10 routine periodic inspection and cleaning should the latter be found necessary. The noise reduction afforded by the silencer must be of a high order so that the submarine may use its internal combustion engines while on the surface without 15 danger of its location becoming known through the presence of exhaust noise.

The exhaust noise of an internal combustion engine consists of a group of relatively low sound frequencies, a group of intermediate sound frequencies and a group of relatively high frequencies. The intermediate frequencies are important in the case of engines employing a large number of cylinders and operating at relative high engine speed. Both low and intermediate 20 frequencies are generally more or less persistent in nature and are readily adapted to being attenuated by the use of acoustic resonators disposed in shunt to the main exhaust conduit. High frequency sounds are relatively simple to 25 attenuate by means of sound absorption, gas turbulence, baffles and the like. In submarine service, evaporators are frequently employed in the exhaust system, in which case they function as high frequency silencers thus making it unnecessary to provide any discrete high frequency 30 silencing means other than that incidental to the low and medium frequency silencing means. In some cases, the evaporator is incorporated in the casing of the silencer proper.

45 In the present invention, low frequency attenuation is obtained by using acoustic sidebranches, one or more of which may be used. In order to meet the requirement that the entire interior of the silencer be quickly and completely flooded with sea water as the vessel submerges, the main gas and sound conducting channel is actually made as two separate channels, through which the exhaust gases pass simultaneously. The channels are in parallel. 50 One of the channels is positioned so as to extend

longitudinally through the silencer at the bottom of the horizontally mounted silencer casing while the other channel extends in like manner along the inside of the top of the casing. Both channels are inaugurated in an inlet chamber and are terminated in an outlet collecting chamber where the exhaust gases are combined before being discharged to atmosphere through a common tail pipe. The inlet chamber may or may not contain other silencing means. If no high 10 frequency silencing means is employed and no evaporator is used, the two parallel channels may be joined by a Y connection. It will thus be seen that sound waves traveling along both channels simultaneously will be substantially in 15 phase. The acoustic sidebranches are coupled to the main channels through acoustic conductivities, preferably in the form of peripheral slots in the main conduits. Thus we have one or more acoustic sidebranches common to both 20 main channels and, provided the phase of the sound waves in these channels are alike, one sidebranch simultaneously serves both upper and lower main channel. Acoustically it would be possible to place a partition inside the volume 25 or space comprising the capacitance of the sidebranch at its nodal plane and the acoustic action would be the same. We would have two sidebranches, each of half the volume and half the 30 conductivity of the system were no such partition present; consequently the frequency response would be unchanged. By leaving out the partition we use the bottom conduit or channel for admitting water to the volume of the sidebranch through the slot-like conductivity and 35 for draining the water therefrom as the vessel comes to the surface. The upper conduit serves as a vent permitting the gas contained in the sidebranch to travel out and along the upper 40 channel to the inlet or outlet compartments where valved vents are provided to permit communication with the open air.

These results can be obtained by using an annular passageway completely surrounding the 45 sidebranch. In this case, however, the conductivity of a slot of the dimensions required to completely girth such an annular channel or the number of discrete holes necessary to provide the proper coupling between the sidebranch and the 50 main channel is so great as to make it difficult to secure attenuation at the desired low frequencies without resorting to very large and cumbersome sidebranches. In the construction herein shown, the conductivities are not unduly large and side- 55

2
branches are readily designed to meet the needs of the service.

Inasmuch as silencers suitable for use on submarines are water-jacketed, the external vents are necessarily placed at the ends of the silencer, rather than on the casing shell. The presence of a water jacket precludes the use of handholes placed in the shell of the silencer. Such cleanout or inspection holes are therefore placed in the transverse headers defining the acoustic side-branches and are made large enough for a man to pass through, thus gaining access to the entire interior of the silencer.

For a further and better understanding of the invention, reference is now made to the drawing, in which.

Fig. 1 shows a longitudinal section in diagrammatic form of one embodiment of the invention;

Fig. 2 shows a section on line 2-2 of Fig. 1;

Fig. 3 shows another embodiment of the invention; and

Fig. 4 shows a section on line 4-4 of Fig. 3.

Referring to Fig. 1, the silencer comprises a cylindrical casing 1, an end header 2 having a centrally disposed inlet connection 3, and a header 4 having an eccentrically disposed connection 5. The interior of the casing 1 is divided longitudinally into five compartments by transverse headers 6, 7, 8 and 9. Each of these headers is provided with two openings, each tangent at its outer edge to the casing 1 and centered on the vertical diameter of the circular header, to permit conduits 10 and 11 to extend longitudinally from the header 6 to the header 9. Each of these conduits 10, 11 is furnished with slot-like peripheral openings at points intermediate each adjacent pair of transverse headers, whereby both of said channels are acoustically coupled into their corresponding sidebranches. The slot-like openings are positioned in an identical manner in each of the conduits 10, 11 so that any given sidebranch volume is acoustically the same distance from the inlet end of said conduits as measured along either channel. This assures the proper phase relations being maintained. Otherwise it would be possible for sound waves to enter the sidebranch chambers from one main conduit and leave through the other, thus interfering to some extent with the proper action of the device. The main channel 10 has, for instance, a conductivity or inertance formed by the slot 12 and the main channel 11, a conductivity formed by the slot 13, each simultaneously opening into the closed chamber 14 formed by the casing 1, the transverse partitions 6, 7, and the outer surfaces of those portions of said conduits which lie between said headers. In other words, the volume or capacitance of the resonator sidebranch is that of a cylinder less the volume taken up by the two main channels passing therethrough. The resonant frequencies of this sidebranch are readily calculable by those skilled in the art.

Similarly, the conductivities 15, 16 and the volume 17 form another resonator disposed in shunt to the main channels, while the conductivities 18, 19, together with the volume 20 form a third sidebranch. The longitudinal spacing of the various headers determines the relative volumes of the various sidebranches. These may be all the same or all different. Since the designer of the silencer generally knows in advance, through measurements in the field, what the frequency range to be attenuated is, it is readily possible to design the low frequency traps so that ample coverage

will be obtained. The space 21, formed between the header 4 and the partition 6, serves as a combining chamber for the two main channels 10, 11, whereby the exhaust gases are directed out through the eccentric outlet connection 5. It is found that this eccentric opening 5 not only permits quick draining of the interior of the silencer but, by making the acoustic paths to the entrance of the two main channels of slightly different lengths, serves to increase the attenuation offered by the silencer as a whole through introducing reflection losses in the space 21. The chamber 22, formed within the casing 1 and between the header 2 and the partition 9 serves as an inlet chamber for the two main channels and, in this embodiment, houses either the high frequency silencing unit shown diagrammatically as 23 or a suitable evaporator.

The interiors of the chambers 16, 17, and 20 are made accessible for inspection and cleaning by means of man holes having suitable cover plates. For instance, the transverse partition 9 is fitted with the man hole 24 and its corresponding cover plate 25. Similar man holes are provided in the partitions 7, 8 whereby the interiors of the chambers 16, 17 are readily accessible. The inlet header 2 is made removable so that the evaporator or high frequency silencing unit may be withdrawn, thus exposing the man hole cover plate 25, which may then be removed. Gas vents 26, 27 are provided at the upper edges of the end headers 2, 4 respectively.

Fig. 3 shows a construction similar to that of Fig. 1 with a modification in the man hole design. In the case of silencers for the auxiliary engines of the submarine, the device may be so small as to preclude the possibility of there being space enough for a man to pass through a cleanout hole. In this case, hand holes are provided. This limits the number of closed sidebranches of this type to two, since the hand holes must be placed in the outer headers defining the low frequency silencing unit. A high frequency silencing unit is shown attached to the inlet head. The silencer comprises the casing 28, the transverse headers 29, 30, 31 and a similar arrangement of main channels and a similar arrangement of main channels and volumetric sidebranches. Sidebranch 32 is accessible through hand hole 33 and sidebranch 34 is accessible through hand hole 35. Both end headers 36, 37 are removable. The inlet header 36 is fitted with a centrally disposed inlet opening 38 and supports a high frequency unit 39, which may be of any conventional construction, while the outlet header 37 has an eccentric outlet opening 40.

In the embodiment shown, the water jacket is omitted for purposes of clarity.

I claim:

1. An acoustic silencing device comprising a pair of main sound conducting channels, means for coupling said channels in parallel to a source of sound waves, and a closed acoustic sidebranch substantially surrounding both of said channels and acoustically coupled to each of them.

2. An acoustic silencing device comprising a pair of main sound conducting channels, means for coupling said channels in parallel to a source of sound waves, and a closed acoustic sidebranch substantially surrounding both of said channels and acoustically coupled to each of them through peripheral slots in the channels.

3. A device of the class described comprising a member defining a cylindrical cavity and a pair of conduits passing therethrough in a direction

parallel to the axis thereof, said conduits being formed with openings whereby said cavity is acoustically coupled to each of said conduits.

4. A silencer comprising a pair of substantially horizontally disposed main sound conducting channels arranged one above the other in a substantially vertical plane and one or more closed acoustic sidebranches each acoustically coupled to each of said channels at points along its length.

5. An acoustic silencing device comprising a pair of sound conducting channels, and an acoustic sidebranch coupled to both of said channels by conductivities having substantially equal 15 acoustic paths thereto from the sound-receiving ends of said channels.

6. An acoustic silencing device comprising a pair of substantially straight sound and gas conducting channels extending horizontally and arranged one above the other in a vertical plane, and an acoustic sidebranch coupled to both of said channels and closed except for said coupling, substantially the entire volume of the sidebranch being above the bottom of the lower channel and 25 below the top of said upper channel.

7. An acoustic silencing device comprising a pair of main sound conducting channels, means for coupling said channels in parallel to a source of sound waves, and an acoustic sidebranch 30 acoustically coupled to both of said channels at points where said sound waves in the respective channels are in phase one with another and closed except for said coupling.

8. A silencer comprising a generally cylindrical casing, a plurality of longitudinally spaced transverse partitions dividing said casing into a plurality of longitudinally spaced cylindrical compartments, and a pair of gas and sound conducting channels connected in parallel and passing through said casing and partitions and each acoustically coupled to each of said cylindrical compartments.

9. A silencer comprising an inlet chamber, an outlet chamber, a pair of substantially straight sound and gas conducting channels connected in parallel between said chambers, and at least one acoustic sidebranch acoustically coupled to each of said channels through peripheral slots in the channels and closed except for said coupling.

10. A silencer in accordance with claim 9 in which the channels have their axes horizontally disposed and lying in a common vertical plane.

11. A silencer in accordance with claim 9 in which the slots in the several channels are identically spaced along the lengths thereof.

12. A silencer for internal combustion engines comprising a generally cylindrical casing, a plurality of transverse headers therein dividing the casing into a plurality of cylindrical compartments, an inlet chamber at one end of the casing, an outlet chamber at the other end of the casing, sound and gas connections into and out of said inlet and outlet chambers respectively, a 65 pair of substantially straight main sound and gas conducting channels in parallel extending from said inlet chamber to said outlet chamber, said channels being disposed horizontally in the same

vertical plane and each being substantially tangent to the inner surface of said casing, and a plurality of acoustic sidebranches disposed within said cylindrical compartments, coupled acoustically to each of the main channels by peripheral slots in the channels, and closed except for said coupling, said slots in the several channels being identically spaced along the lengths thereof.

13. A silencer for both high and low frequencies comprising a casing, at least one main sound and gas conducting channel passing through the casing, a plurality of transverse headers within the casing forming between them a plurality of acoustic sidebranches acoustically coupled to said channel but closed except for said coupling, a 15 removable high frequency silencing unit positioned within one end of the casing, and man holes in the transverse headers to permit access to the interior of the closed acoustic sidebranches when the high frequency silencing unit has been 20 removed.

14. In a device of the class described, a cylindrical casing defining a cavity, and a pair of conduits passing through said cavity in a direction parallel to the axis thereof, said conduits being 25 acoustically coupled to said cavity at points such that sound waves emanating from a common source and traveling through said conduits are substantially in phase.

15. A silencer comprising a pair of main gas and sound conducting channels of substantially equal length, means for coupling said channels in parallel to a common source of sound, a plurality of acoustic sidebranches disposed in shunt to both of said channels along the lengths thereof and each acoustically coupled to each of said channels and closed except for such coupling, the spacing and formation of said couplings between the channels and the sidebranches being substantially identical in each of the channels, 40 whereby certain groups of sound frequencies traveling in phase simultaneously through said channels are highly attenuated by said sidebranches.

16. A silencing device comprising a pair of spaced main sound conducting channels, an 45 acoustic sidebranch coupled to one of said channels by an opening at the top thereof and to the other of said channels by an opening at the bottom thereof, and means for connecting said channels in parallel for the conduction of sound 50 simultaneously therethrough.

17. A silencing device comprising a pair of substantially horizontally arranged sound and gas conducting channels arranged one above the other, and at least one acoustic sidebranch interposed between the two channels and acoustically coupled to both of them through openings therein, the relative positions of the channels, the sidebranch, and the openings being such that water may enter said sidebranch through the 60 opening therefrom into the lower main channel and completely fill the interior volume of said sidebranch, the imprisoned gas or air passing out through the conductivity in said upper channel so that both the channels and the sidebranch 65 can be quickly and completely filled with or emptied of water.
